Cyrus R. Dostwick INVENTOR
BY
Alfred S. Kent ATTORNEY

UNITED STATES PATENT OFFICE.

CYRUS R. BOSTWICK, OF MARIPOSA, NEW YORK, ASSIGNEE OF ONE-HALF TO HENRY WALLACE, OF GLEN RIDGE, NEW JERSEY.

CAR SEAL.

Application filed April 1, 1921. Serial No. 457,790.

To all whom it may concern:

Be it known that I, CYRUS R. BOSTWICK, a citizen of the United States, residing at Mariposa, in the county of Chenango and State of New York, have invented certain new and useful Improvements in Car Seals, fully described and represented in the following specification and the accompanying drawing, forming a part of the same.

10 This invention relates to car seals, and has for an object to provide a device for sealing the doors of freight cars which shall also serve as a tag showing the points of origin and destination and the date of shipment.

15 It has been customary to seal the doors of freight cars by passing a wire through the staple on the door after the hasp has been placed over the staple, and then securing the ends of the wire together by means of a small metal seal. Such sealing means provides no means for carrying data as to the shipment of the car.

20 In accordance with my invention the device by which the door of the car is sealed is provided with a tag portion upon which are permanently marked letters and figures for indicating the date of shipment, the point or origin, destination, etc. The tag portion is an integral part of the sealing device, so that the car is tagged at the same time that it is sealed.

25 In order that my invention may clearly be understood, I will describe in detail the specific embodiment of it shown in the accompanying drawings, in which:

30 Fig. 1 is a plan view of the sealing device before use;

35 Fig. 2 is a transverse section taken on the line 2—2 of Fig. 1; and

40 Fig. 3 is a view similar to Fig. 2 indicating the position of the tabs and sealing piece after sealing.

The sealing device comprises a tag plate 10 which is most desirably circular in form. 45 From this plate extend two tabs 11 and 12. The plate 10 contains an aperture 13 which is most desirably circular in shape and set off from the center of the plate 10 toward the tabs 11 and 12. The cut 14 which separates the tabs 11 and 12 opens into the aperture 13.

The plate 10 and tabs 11 and 12 are made from a single piece of flexible sheet metal.

50 On the tag plate 10 there is permanently marked, as by stamping or cutting or in

other suitable manner, a series of figures, 1 to 31, and the abbreviations for the twelve months. There is also marked on the plate the name of the starting point or place of origin of the shipment and its destination, and, if desired, the name of the railroad. The places of origin and destination may be impressed or otherwise marked on the plate at the time of use, or the plates may be so marked in quantity beforehand, or the plates 65 for use at any particular place of shipment may be marked with the name of such place and have the destination marked thereon as used.

Near the outer end of one of the tabs 70 is a sealing piece 15 which may be composed of lead or other suitable metal. The sealing piece 15 is U-shaped in cross-section as shown in Fig. 2 and is most desirably attached to the tab by soldering or 75 otherwise, in order to prevent its loss. It is, however, not essential that the sealing piece 15 be attached to one of the tabs beforehand.

In using the sealing device shown in the 80 drawings, the place of origin and destination are first marked upon the tag plate 10 unless already thereon. The date of shipment is then indicated by punching out of the plate 10 the month and the number 85 indicating the day of the month upon which the shipment takes place. The tabs 11 and 12 are then spread apart and the device is slipped over the staple on the car door after the hasp has been closed, so that the 90 staple passes through the aperture 13. The tabs 11 and 12 are then overlapped and the end of the tab 11 is brought over the end of the tab 12 within the sealing piece 15.

The sealing is effected by applying a 95 heavy pressure to the opposite sides of the sealing piece 15, so that it is forced against the ends of the tabs 11 and 12, as shown in Fig. 3. The car door is thus effectively sealed and at the same time a tag is sealed 100 to it. This tag remains on the car until the car is opened at its destination. It serves to indicate the proper destination of the car, so that the car does not become lost en route. Furthermore, it serves to indicate to 105 the consignee the date of shipment as well as the point of origin of the shipment.

When the car is opened the sealing piece 15 is pried or broken apart so that the tab 11 may be withdrawn from the tab 12 and 110

the tabs spread apart so as to permit the removal of the device from the staple. The tag may be punched to indicate the date, that is, the month and day, of arrival, a 5 punch of different shape from that by which the day of shipment was indicated being desirably used. The tag plate may be filed away as a permanent record of the shipment.

10 My invention is by no means limited to the exact form and arrangement of parts shown in the drawings. Among the modifications which may be made are changes in the shape of the tag plate 10 and the 15 shape and position of the aperture 13. Furthermore, means other than the sealing piece 15 may be used for sealing together the ends of the tabs 11 and 12.

What is claimed is:

20 1. A tag for the doors of freight cars, comprising a tag plate having an aperture therein, and two closely spaced tabs extending from adjacent portions of the periphery of said plate, the opening between the tabs 25 extending to the aperture in the plate, the tag being made of a single piece of sheet metal of sufficient flexibility to permit overlapping of the outer ends of the tabs so that they may be sealed together, and means 30 for securing the outer ends of the tags together when overlapped.

2. A tag for the doors of freight cars, comprising a circular tag plate having an

eccentrically placed aperture therein, and two closely spaced tabs extending outwardly 35 from adjacent portions of the part of the periphery of said plate nearest said aperture, the opening between said tabs extending radially to said aperture, the tag being made of a single piece of sheet metal of sufficient flexibility to permit the overlapping 40 of the outer ends of the tabs so that they may be sealed together.

3. A metal tag for the doors of freight cars, comprising a tag plate having permanently marked upon it a series of abbreviations and numbers by means of which a date 45 may be indicated by punching, said tag plate having an aperture therein and an opening extending outwardly from said 50 aperture to the periphery of said tag plate, and closely spaced tabs extending from the portions of the periphery of said tag plate adjacent to said opening at opposite sides thereof, the tag being made of a piece of 55 sheet metal of sufficient flexibility to permit the outer ends of the tabs to be overlapped so that they may be sealed together.

In testimony whereof I have hereunto set my hand in the presence of two subscribing 60 witnesses.

CYRUS R. BOSTWICK.
